SNUG STOWING ANCHOR

Donald Linnenbank, Chester, Pa., Fred B. Money, Thorofare, N. J., and Dwight P. Noel, Jr., Crum Lynne, Pa., assignors to The Boston Metals Company, Chester, Pa., a corporation of Maryland

Application April 7, 1951, Serial No. 219,842

1 Claim. (Cl. 114—208)

1

This invention relates to a ship's anchor of the stockless type consisting primarily of two members, that is, a shank member and a crown and fluke member. The latter is designed to lie flat against the hull of a ship when the shank is drawn up into the hawse pipe. For this purpose the crown and fluke member is substantially the combination of a flat slab which tapers gradually in thickness from its rear end forward to the tips of the flukes with a head portion which projects symmetrically in both directions from the plane of the flukes, each such projection being adapted to enter the mouth of the hawse pipe so that the flukes can lie flat against the hull, there being no other projections out of the plane of the flukes. At the base or rear end of the flukes are two aligned, laterally projecting stabilizing arms which are integral with and in the same plane as the corresponding flukes. The head portion of the crown and fluke member contains a socket in which is received a ball formed at the rear end of the shank. The head portion also has a slot which is forward of and narrower than the portion of the shank adjacent to the ball. This permits relative rocking movement between the shank and the crown and fluke member. The side faces of the shank are preferably plane, but the upper and lower faces are rounded, preferably having a curvature equal to that of a cross-section of the hawse pipe. The ends of the slot in the head are concaved correspondingly to be fitted by a rounded face portion of the shank when the crown and fluke member is rocked with respect to the shank to its limit in either direction. The portions of the head which project from the plane of the flukes serve as tripping scoops to dig into the ground and thus to cause the crown and fluke members to rock as the anchor is dragged along the ground, thus causing the points of the flukes to dig into the ground so as to bury the flukes.

For a more complete understanding of the invention, reference may be had to the following description thereof and to the drawing, of which—

Figure 1 is a perspective view of an anchor embodying the invention;

Figure 2 is a sectional view on the line 2—2 of Figure 1;

Figure 3 is an elevational view of the anchor held in an upright position with the shank and flukes in a common plane;

Figure 4 is a section on the line 4—4 of Figure 3;

Figure 5 is an elevational view of a portion

2

of a hull showing the anchor stowed in place;

Figure 6 is a fragmentary sectional view of the hull shown in Figure 5 and the anchor stowed in the hawse pipe; and

Figure 7 is a sectional view on the line 7—7 of Figure 6.

The anchor illustrated on the drawing is of the stockless type consisting of two major members which are rockably connected together. One of these members consists of a shank 10, the other member being a unitary crown and fluke member comprising two flukes 12 and 16 extending forward from tripping head portions 18, and laterally projecting arms 20 and 22 to stabilize the anchor. The flukes 12 and 16 with their respective arms 20 and 22 lie in a common plane and constitute a slab which tapers gradually in thickness from a maximum at the rear end or base of the flukes forward to the tips of the flukes. The arms 20 and 22 are preferably in the same straight line and project beyond the outer edge of the flukes so as to prevent the anchor from rolling over on the axis of the shank when it is dragged along the bottom. The head portion 18 projects in both directions from the plane of the flukes and arms, these two projections being the only portions of the crown and fluke member projecting from such plane. The head portions 18 are located at the base of the flukes and between the arms 20 and 22 which extend in opposite directions therefrom. The tripping head is hollow and contains a socket 24 which is shaped to receive a ball 26 formed on the rear end of the shank 10. Communicating with and forward of the socket 24 is a slot 28 in the head 18, this slot being narrower than the socket 24 but slightly wider than the portion of the shank 10 which is adjacent to the ball 26 as indicated in Figures 3 and 4. The ball 26 and the socket 24 form a ball and socket joint which permits the crown and fluke member to rock through a limited angle with respect to the shank 10 so that the shank can extend at an angle of approximately 45° to the plane of the flukes, on either side of such plane. The limit of such relative rocking movement is determined by the end walls 32 and 34 of the slot 28, these end walls being engaged by the shank 10 when the latter has swung to one or the other of its limiting positions. The shank preferably has a cross section such as is illustrated on Figure 2, with straight sides 36, 38 and rounded top and bottom faces 40 and 42. The corner edges 44 of the shank are rounded off with a greater curvature than the top and bottom faces 40 and 42.

The curvature of the top and bottom faces is preferably equal to the curvature of a cross section of the hawse pipe 46 into which the anchor is intended to be drawn when not in use. When an anchor which is attached to a chain cable is being raised, the planes of the successive links are at right angles to each other so that as the chain cable is drawn through the hawse pipe, the planes of the links are inclined with respect to the surface of the hawse pipe with which the links are in actual contact. This means that when the shackle 48 at the forward end of the shank 10 reaches the hawse pipe, the anchor is turned about 45° from the angular position the shank will assume when the anchor has been drawn up into the pipe. Thus the anchor must turn itself through an angle of 45° while the shank is being drawn into the hawse pipe. The curvature of the top and bottom faces 40 and 42 of the shank, as well as the rounded edges 44, facilitate this turning movement of the anchor about the axis of its shank as it is drawn into the hawse pipe.

The curvature of the top and bottom faces of the portion of the shank which is adjacent to the ball 26 is also useful in tending to prevent cocking of the shank when the shank is rocked to one of its limiting portions. For this purpose the end walls 32 and 34 of the slot 28 are concaved with a curvature similar to that of the shank surfaces by which they may be engaged. The convex shank surface fitting into a corresponding concave end wall of the slot tends to maintain the shank in a plane perpendicular to the arms 20 and 22 when the shank engages one or the other of the end walls of the slot.

The head portions 18 which extend from the plane of the flukes and arms are of somewhat irregular shape but each such portion has a substantially semicircular contour outline when projected on a plane which is perpendicular to the axis of the shank 10 when the shank is in one or the other of its limiting positions. Such contour is shown in Figure 7, the curvature being such that one of the head portions 18 will fit snugly into half of the circumference of the hawse pipe when the anchor is stowed therein. This, together with the shank and adjacent portion of the flukes, effectively blocks the hawse pipe so as to prevent sea water from surging up through the pipe when the bow of the vessel dips into waves. Since the head portions are of such a size and shape that either can enter the hawse pipe, the flukes and arms can be drawn up against the hull so as to lie flat against it and present a minimum of surface to water, ice, flotsam, or the like which may be cast against the bows of the vessel. When one head portion is within the hawse pipe, the other one necessarily projects outward from the plane of the flukes, but this outwardly projecting head portion presents a somewhat spherical surface outward and is the only portion of the anchor projecting from the plane of the flukes.

The socket 24 opens to the rear of the anchor so as to receive the shank when the members are

to be assembled. When the ball has been fitted in the socket a retaining pin 50 is mounted to the rear thereof, this pin passing through a pair of ears 52 and 54 which project rearward of the head portion 18. In order to provide additional facial area for the flukes and also to reduce the weight of the anchor, the head projections are relieved as at 56.

While the ratios of the various dimensions of the anchor may vary to some degree, it is preferred that the extreme width of the anchor, that is, the distance between the extremities of the arms 20 and 22 be about 92% of the shank length, and that the maximum transverse dimension of the head portions 18, which appears as the vertical height of the illustration in Figure 4 of the drawing, be about 35% of the shank length. The thickness of the slab portion of the crown and fluke member preferably tapers from 6 1/2% to 2 1/2% of the shank length.

We claim:

A stockless anchor for ready engagement with a generally cylindrical hawse pipe comprising a shank having cable-attaching means at one end thereof, and a unitary crown and fluke member pivotally connected to the other end of said shank and rockable from a plane containing the axis of the shank through a limited angle in either direction, said crown and fluke member including a tripping head, stabilizing arms projecting in opposite directions outwardly from said tripping head, flukes extending forwardly from the inner portions of said arms and immediately adjacent the shank, said arms and flukes being substantially flat and coplanar, said tripping head comprising symmetrical portions projecting in opposite directions from the plane of said arms and flukes, each said portion having a generally semicircular contour when projected on a plane perpendicular to the axis of the shank when the shank is in limiting position adjacent said portion, whereby when the shank of the anchor is drawn snugly into a ship's hawse pipe having a diameter approximately equal to the diameter of said semi-circular contour either tripping head portion fully enters into the generally cylindrical hawse pipe and together with the shank and the adjacent portions of the flukes substantially blocks the hawse pipe, and said arms and flukes rest generally flat against the side of the ship.
